UNITED STATES PATENT OFFICE

101,099

DESIGN FOR A SHOE

Haviland D. Baldwin, Auburn, Maine, assignor to
Ault-Williamson Shoe Co., Auburn, Maine, a
corporation of Maine

Application January 20, 1936, Serial No. 60,670

Term of patent 3½ years

To all whom it may concern:

Be it known that I, Haviland D. Baldwin, a citizen of the United States, residing in Auburn, in the county of Androscoggin and State of Maine, have invented a new, original, and ornamental Design for a Shoe, of which the following is a specification, reference being had to the accompanying drawing, forming a part thereof, in which

Fig. 1 is a plan view of a shoe showing my design; and

Fig. 2 is a view of a shoe in side elevation, the heel being shown conventionally in dot and dash lines.

The dominant feature of my design resides in a foxing strip extending rearwardly from the tip of the shoe, having serrated inwardly curved longitudinal edges, and passing beneath the surface of the vamp at about the instep line of the shoe and covered at its rear end by convergent curved edges of the vamp which meet in a point.

I claim:

The ornamental design for a shoe substantially as shown and described.

In testimony whereof, I have affixed my signature hereto.

HAVILAND D. BALDWIN.
